UNITED STATES PATENT OFFICE.

FREDERICK PEITER, OF CLEVELAND, OHIO, ASSIGNOR OF ONE-HALF TO ARTHUR G. MCKEE & COMPANY, OF CLEVELAND, OHIO, A CORPORATION OF PENNSYLVANIA.

GAS AND AIR CONTROLLING MEANS FOR COKE-OVENs.

1,291,109.

Specification of Letters Patent. Patented Jan. 14, 1919.

Application filed September 5, 1916. Serial No. 118,355.

To all whom it may concern:

Be it known that I, FREDERICK PEITER, a citizen of the United States, residing at Cleveland, in the county of Cuyahoga and State of Ohio, have invented a certain new and useful Improvement in Gas and Air Controlling Means for Coke-Ovens, of which the following is a full, clear, and exact description, reference being had to the accompanying drawings.

This invention relates generally to coke ovens and more particularly to certain operative means for carrying out the process described in my application filed August 8, 1916 Serial No. 113,769.

In the aforesaid application I have clearly pointed out the serious objections to the method or process of coking coal ordinarily employed and I have also described my novel method whereby these objections are overcome, said process or method consisting broadly in supplying to the combustion flues at the beginning of the coking operation, an amount of combustible gas and air sufficient to produce all of the heat which can be safely and efficiently transmitted to the coal mass to be coked, whereby the preheating of the coal and the initial coking operation is materially expedited, the supply of combustible gases and air being gradually reduced as the coking operation continues until at the end of the coking period the amount is about the same, or slightly less than has been heretofore used during the whole operation, thereby avoiding the overheating of the brick work during the latter part of the coking operation, decreasing the amount of "cauliflower" coke produced and producing a better grade of coke in a shorter space of time.

The isothermal method of coking coal above described, and means for practising this method consists, in the main, of the usual equipment of a by-product coke oven plant, to which must be added means for gradually throttling the gas supply and air passing to the flues of each oven as the coking progresses. This means would of course be quite independent of the usual means for reversing the flow of air and waste gases through the checkers, it being arranged, as it is, solely for the purpose of controlling the quantity of gas and air being delivered to each oven.

There are several ways in which this may

be done. The first means suggesting itself would be to open the reversing valve a less amount each time, but as all of the ovens of a battery are controlled by one reversing mechanism and as some of them would be nearly coked while others would be just starting it would seem to unnecessarily complicate the equipment and it is with the view of producing a simple and highly efficient means that I have devised the present operative means.

It is the underlying principle of my invention to control the temperature in the flues so as to produce the best quality of coke from available materials, and in the shortest time consistent therewith, regardless of whether this control shall be such as to maintain the maximum temperature safely attainable throughout the entire operation, or such variation of this maximum as may be found most desirable.

In the drawings forming a part of this specification, Figure 1 is a sectional view partly in elevation of one end of a coke oven to which my improved operative means is connected; Fig. 2 is a detail view partly in section of the gas valve and reversing mechanism; Fig. 3 is a plan view of the same; Fig. 4 is a sectional view partly in elevation on the line 4—4 of Fig. 3; Fig. 5 is an enlarged sectional view of the damper controlling the air duct; and Fig. 6 is a plan view of the same.

Fig. 7 is a diagrammatic plan view of a type of mechanism which may be employed for synchronously throttling the gas and air supply.

Fig. 8 is a vertical sectional view thereof on the line 8—8 of Fig. 7;

Fig. 9 is an end elevation of the structure illustrated in Fig. 7.

In the general view of Fig. 1 I have shown but one end of an oven, and it will be understood that the opposite end of the oven is equipped with means substantially the same as that shown in Fig. 1.

In practice I prefer to use a separate valve or throttling device in the air and gas pipes or ducts between the reversing valve and the oven burners and in carrying out this idea I employ a shaft 10 mounted in a bracket 11 at a point adjacent the gas valves, and upon this shaft is mounted the reversing arm 12 adapted to alternately engage the stems 13 of the valves 14 controlling the inlet of gas.

to the burner pipes 15. The casings 16 of the valves 14 are connected to a central casing 17 which has communication with the gas supply pipe 18, and working in this central casing 17 is a throttle valve 19 having a depending stem 20 the end of which is engaged by a cam 21 mounted upon the shaft 10 and having integral therewith a ratchet wheel 22 which is engaged by the working pawl 24, pivotally connected to the reversing arm 12 and held against return movement by a pawl 23, so that at alternate reversal of the gas the ratchet wheel will be moved one tooth carrying with it the cam which, as before stated, is in operative engagement with the stem of the throttling valve and therefore operates said valve to control the supply of gas. It is usual to make the reversal once every thirty minutes and consequently the number of teeth upon the ratchet wheel would be determined by the coking time and in the present instance sixteen teeth are shown which would make the coking period sixteen hours but it will of course be understood that the ratchet wheel can be made any convenient size and provided with any desired number of ratchet teeth in order to provide for one complete revolution of the cam for each coking operation. The cam 21 is designed with the idea of causing a maximum amount of gas to be delivered to the combustion flues at the start, and then gradually reducing or throttling the supply as the flow of heat is retarded due to the increased temperature of the brick adjacent to the coking coal, so as to maintain the combustion flues constantly at the maximum temperature safe for the refractories and at all times during the coking operation transmit the maximum possible number of heat units consistent with such safety.

It may not be possible to attain the theoretical perfection of operation just mentioned, but it is possible to closely approximate it, by taking into consideration the facts regarding the differences in temperatures between the combustion flues and the coal when first charged into the oven and also the heat resistance of the intervening wall of brick and coke and the heat units transmitted per minute during the coking operation, assuming uniform temperature in the combustion chamber.

Owing to the low temperature of the coal mass and the high temperature of the burning gases the conduction of the heat will at first be very rapid.

The resistance of the intervening wall of brick and coke, gradually increases and the cam 21 is therefore constructed with a gradual curve 21^a extending from the bottom of an incline 21^a around the cam to the top of the incline and by means of a cam constructed as herein shown and described in connection with the throttling valve, ratchet wheel,

reversing arm and pawls, I am able to supply the maximum amount of gas consistent with safety at the start and gradually throttle the same so as to bring about a regulation of the heat within the combustion flues as hereinbefore described.

In connection with the cam 21 and operating simultaneously therewith is a cam 25 which is mounted upon a shaft 26 near the bottom of the duct 27 and which operates a throttle valve 28 for closing the duct 29 of the regenerator, the throttle valve 28 having a push rod 30 connected thereto and against which the cam 25 bears for the purpose of forcing the same inwardly to close the duct. Any suitable mechanism can be employed for transmitting motion to the cam 25 and to the shaft 26 and in Figs. 7, 8 and 9 I have shown one construction of operating mechanism in which 31 designates a shaft receiving its power from any suitable source. This shaft carries a crank 32 connected by a link 33 to a toothed segment 34 operating upon a gear 35 mounted upon a countershaft 36 which shaft also carries sheaves 37 around which pass cables 38 connected to the air and waste gas dampers 39 and 40 respectively. The shaft 36 also has a gear 41 mounted thereon which meshes with a gear 42 carrying a crank 43 to which is attached a cable 44 which passes over suitable sheaves and is connected to a depending portion of the rocker arm 12 and is provided with a counterweight 45 at its end. The gears 42 and 41 are in the ratio of 2 to 1. The power shaft 31 is given one-half revolution at each reversal and this causes one revolution of the shaft 36 through the medium of the toothed segment 34 and this complete revolution of the shaft 36 causes a complete reversing movement of the air and waste gas dampers. The gears 42 and 41 being in the ratio of 2 to 1, the crank 43 will make a half revolution at each complete revolution of the shaft 36 working back and forth for the purpose of operating the reversing arm 12, and each alternate movement of this arm causes the ratchet 22 to be advanced one tooth carrying with it the cam 21 which operates upon the stem of the throttling valve. Thus at each reversal of the air and gas the arm is rocked and at each alternate reversal the cam 21 is moved a distance of one tooth of the ratchet 22 and the stem 20 of the throttling valve 19 caused to ride a definite distance upon the gradual curve 21^a of the cam 21. The toothed segment 34 has a second link 46 connected thereto which in turn is connected to an arm 47 carrying a pawl 48 operating upon a ratchet 49 mounted upon a shaft 50. The shaft 50 carries a bevel gear 51 at each end which in turn meshes with gears 52 carried at the upper ends of shafts 53 carrying bevel gears 54 meshing with gears 55 upon

the shaft 26 so that as the cam 21 is moved one step at a time to throttle the gas supply, the shaft 26 carrying the cam 25 is moved one step at a time to throttle the air supply. Thus we have the supply of gas and air progressively and gradually reduced after the first period of firing. The push rod 30 can be pulled out by hand whenever it is desired to open the duct 29. The cam 25 is constructed upon the same lines as the cam 21 so that the throttling of the air will be in synchronism with the throttling of the fuel gas.

The apparatus herein shown and described is the preferred construction for accomplishing the operations herein set forth but it will be understood that certain changes and modifications can be made without departing from the broad principle of the invention and within the scope of the appended claims.

Having thus described my invention, what I claim is:—

1. The combination with a by-product coke oven, of means for throttling the supply of gas and air to the combustion flues thereof, and progressively-acting means associated with said throttling means and actuating the latter to progressively throttle the flow of the gas and air.
2. The combination with a by-product coke oven, of means for throttling the gas supply to the combustion flues thereof, means for throttling the air supply to said flues, and progressively-acting means associated with said gas-throttling and air-throttling means and actuating each of the same to progressively throttle the flow of the gas and air.
3. The combination with a by-product coke oven provided with means for reversing the direction of flow of the gas and air through the combustion flues of said oven, of operative means connected with said reversing mechanism for regulating the heat within the combustion flues.
4. In a coke oven, the combination with the combustion flues thereof, and means for supplying gas thereto, of means for throttling the flow of the gas to said flues, and progressively-acting means associated with said throttling means and actuating the latter to progressively throttle the gas in its flow to the combustion flues.
5. In a by-product coke oven the combination with means for supplying gas and air to the combustion flues of said oven, of means for reversing the direction of flow, and means for throttling the supply of gas and air to said flues, said means being operatively connected with the reversing means.
6. In a by-product coke oven, the combination with means for supplying gas and air to the combustion flues of said oven,

means for reversing the direction of flow through said flues, means for throttling the supply of gas, and means for throttling the supply of air, said throttling means operating synchronously and being operatively connected with the reversing means.

7. In a coke oven, the combination with a gas supply valve, of a reversing means, a throttling valve, and means operatively connected with the reversing means for operating said throttling valve.

8. In a coke oven, the combination with a gas valve, of a reversing means, and a throttling means operatively connected with the reversing means and moved step by step thereby.

9. In a coke oven, the combination of gas supply valves and a reversing arm operative in connection therewith to direct the flow of gas in either direction, a throttling valve in connection with said gas valves, a cam for operating said throttling valve, a ratchet wheel connected with said cam, and a pawl connected with the reversing arm and operating upon the ratchet wheel whereby alternate reversals the ratchet wheel and cam are advanced a tooth.

10. In a coke oven, the combination with means for supplying gas and air to the combustion flues thereof, of means for throttling the supply of gas, means for throttling the supply of air, and means for synchronously operating said gas and air-throttling means.

11. In a coke oven, the combination with the combustion flues thereof, of means for supplying gas and air thereto, means for throttling the feed of the gas and air constructed to admit a maximum amount of each to the flues at the initial firing stage, and means acting on said controlling means for reducing the amount of the admitted gas and air as the coking progresses.

12. In a coke oven, the combination with the combustion flues thereof, of means for supplying gas and air thereto, and a synchronized control for the gas and air serving to admit a maximum amount of each to the flues at the initial firing stage and to reduce the amount thereof as the coking progresses.

13. In a coke oven, the combination with the combustion flues thereof, of means for supplying gas and air thereto, a synchronized control for the gas and air serving to admit a maximum amount of each to the flues at the initial firing stage and to reduce the amount thereof as the coking progresses, and intermittently-operating means for effecting said reduction in the amount of the gas and air during said progressive stages of the coking.

14. In a coke oven, the combination with the combustion flues thereof, means for supplying gas and air thereto, and means for reversing the direction of flow of the gas and air to said flues, of synchronized throt-

tling means for the gas and air serving to admit a maximum amount of each to the flues at the initial firing stage and to reduce the amount thereof as the coking progresses,
5 and connections between said reversing means and said throttling means for actuating the latter at periodic reversals of the direction flow of the air and gas in the flues.

10 15. In a coke oven, the combination with

the combustion flues thereof, of gas and air throttling means serving to admit a maximum amount of each to the flues at the initial stage of firing and to reduce the amount thereof as the coking progresses, and a common driving means for said throttling means.

In testimony whereof, I hereunto affix my signature.

FREDERICK PEITER
